VICTOR H. EMERSON, OF NEW YORK, N. Y., ASSIGNOR TO VOICE RECORDER COMPANY, INC., OF NEW YORK, N. Y., A CORPORATION OF NEW YORK.

DEVICE FOR REPOINTING PHONOGRAPH-NEEDLES.

1,360,511.

Specification of Letters Patent.

Patented Nov. 30, 1920.

Application filed March 7, 1918. Serial No. 220,972.

To all whom it may concern:

Be it known that I, VICTOR H. EMERSON, citizen of the United States, and resident of New York, in the county of New York and State of New York, have invented certain new and useful Improvements in Devices for Repointing Phonograph - Needles, of which the following is a specification.

My invention relates to improvements in devices for re-pointing phonograph needles; and especially such devices as can be most conveniently operated by means of the talking machine for which such needles are intended to be used.

15 An object of my invention is to provide a re-pointing device which is capable of quickly and efficiently sharpening the end of the needle of a talking machine, and is simple in structure and operation, so that 20 any one, however unskilled, may easily utilize it to obtain the desired results.

A further object of my invention is to provide a re-pointing device which can be readily applied to a talking machine and actuated by a readily accessible moving part of the latter, for example, the turn-table; and which also is easily dismounted and removed when the re-pointing operation is completed, thus leaving the talking machine in condition 30 to reproduce a record without requiring restoration of any of its parts, or other readjustment.

It is well known that needles for modern talking machines in order to reproduce properly the sounds from which a phonographic record is derived, are required to be sharpened to a high degree of fineness, to fit into the minute channel of the groove in which the sound waves are recorded. The point of 35 the needle furthermore is conical in form, and thus when new presents dull or rounded surfaces to the walls of the sound grooves with which it come in contact. To further preserve the needle contacting surfaces of 40 the sound records, they are formed of a hard, wear-resisting material. The fine rounded point of the needle itself becomes worn after use for only a short period, receiving a flat surface upon the side of the needle 45 where the abrasion is the greatest. This flattened surface, although of very minute dimensions, results in forming at the engaging point of the reproducing needle a cutting or chisel-like edge, which if continued in use would soon destroy the record with 50 which it should be used. Hence such needles,

after being used a very few times, and by many operators only once, are thrown away and new ones substituted, which not only entails needless waste, but often through inadvertence in using a damaged needle, will seriously injure if not actually destroy a valuable sound record. My invention therefore will be advantageously employed to re-point phonograph needles by working them in a convenient and expeditious manner that is not only attended with an infinitesimal loss of the material of the needle, but by the restoration of the original contour, and as a result the "lives" of the needles can be extended for a practically indefinite period.

The above and other objects and advantages of my invention will fully appear in the following description, taken in connection with the accompanying drawings forming a part of the same; and the novel features of my invention will be precisely defined in the appended claims.

Having reference to the drawings, which illustrate an embodiment of my improved re-pointing device,

Figure 1 is a side elevation of a re-pointing device made according to my invention; and

Fig. 2 is a front elevation of that one of the parts of the device by which the re-pointing of the needles is immediately effected.

In the particular description of the embodiment of my invention herein disclosed, I employ the numeral 1 to indicate the base or casing of a phonograph or talking machine, having a suitable tone-arm 2 and a revoluble turn-table 3. The tone-arm is illustrated only in part, but it is to be understood that this tone-arm will be of the usual construction, and that it may carry a sound box with the reproducing needle held therein.

The tone arm will be mounted on the base 1 near the turn-table 3, and in such fashion that it can swing to the required extent to permit the needle it bears to follow up the sound grooves of a tablet on the turn-table 3. The turn-table will be capable of rotation by a shaft 4, on which it is supported in the conventional manner, its upper face being provided with the centering stud or pin 5. No part of this construction is claimed as novel, and for that reason is not deemed necessary to be shown or otherwise set forth with any greater degree of fullness than is here presented; for my inven-

tion is designed to be used in conjunction with any type of talking machine having a base, a turn-table and a center pin, as will plainly appear hereinafter.

5 I also show at 6 a working member preferably in the form of a peculiarly grooved disk of abrasive material of predetermined fineness of grain, such as emery, carborundum or other grit; and this disk is rotatably 10 mounted on an element or bar 7. My invention comprises as essential elements, whether considered in and for themselves alone, or in combination with a movable part of a talking machine such as the turn-table 3 above mentioned, the disk 6 and a 15 suitably supporting member such as the bar 7. The disk 6 in the form illustrated is rotatably attached to one end of the bar 7 by a screw 8, which serves as a pivot or 20 journal upon which the disk 6 is adapted to turn. On the bar 7 is provided a laterally extending recessed boss 9, which is adapted to fit upon and receive in the recess thereof the center pin 5. Hence, if the periphery of 25 the disk 6 rests in contact with the upper face of the turn-table 3, and the pin 5 enters the boss 9, rotation of the turn-table 3 will rotate the disk about the screw 8 as an axis, if the bar 7 be held against movement. The 30 supporting bar 7 is therefore in the preferred form illustrated prolonged beyond the boss 9, so that an end will be in contact with the tone-arm 2, or some other stationary part of the talking machine or casing 35 thereof; thereby maintaining the disk 6 and the turn-table 3 in operative relation.

In one face of the disk formed in the material thereof is an annular groove or recess 10, which is preferably formed in 40 semi-circular cross-sectional area, or more particularly designated should preferably have its outer or larger surface rounded as shown. The groove may be made of any convenient size either as to the diametral 45 or cross-sectional dimension thereof, but in practice I have found satisfactory results with such groove from two to three inches in mean diameter, and that such groove recessed to a depth and width of from one 50 quarter to three eighths of an inch will have a capacity for handling successfully in excess of one hundred needles of the ordinary size. The groove is adapted to be covered by a closure 11 which in its simplest form 55 may be of metal, as shown in the drawing. Obviously other materials may be employed for this member, which while subserving the main purpose of a simple closure, might have added advantages. For example, if 60 made of a transparent material such as celluloid, the contents could be more readily inspected in process of repointing, thereby rendering unnecessary the removal of the plate for the purpose. Or for the purpose

of increasing the effective abrasive surface 65 of the device as a whole, the closure 11 could itself be made of abrasive material or supplied with such lining at the position of the annular groove, which may be in the shape of a plate of any suitable material, held 70 in place by the head of the screws 13 passing through the necked slots 14 of the closure plate 12.

In operation, a number of needles to be repointed are placed in the groove 10, and are 75 prevented from falling out of this groove by the plate 11. The needles are indicated in Fig. 2 by the numeral 12, this figure showing the disk as it appears with the closure 11 removed. The groove 10 being 80 formed concentric with the axis of rotation of the disk or member 6, as the latter rotates, the ends of the needles rub against the side of the groove or recess which is farthest from the axis of rotation of the 85 disk, and speedily becomes sharpened and thereby fitted for further service.

With the various parts in the positions shown in Fig. 1, the turn-table is supposed to be revolving in such a direction that the 90 left side is moving toward the observer. Hence the disk will be rotating counter-clockwise, when viewed upon the side having the groove 10. The needles in the groove 10 will preferably be placed in such position that their ends to be repointed are turned in the direction of the rotation of the disk; so that their ends to be sharpened will be engaged to the best advantage. As 95 many needles may be placed at one time in the groove 10 as the latter will conveniently hold; but it is a necessary condition of operation that the needles must not be packed in the groove 10, but should be loosely placed in same, so that they may move about 100 in the required degree as the disk is rotated by the turn-table 3.

As the disk 6 turns, the needles 12 will tend to revolve about the axis of rotation of the disk; but on account of their inertia and 110 the action of gravitation, they will not revolve at the same angular speed as the disk. Moreover, the centrifugal force due to the rotation of the disk 6 will tend to carry the needles away from the inner side of the 115 groove toward the side which is farthest from the screw 8 circumferentially of the groove. Further, as the needles are carried by the disk 6 into different successive positions, they necessarily slide upon their ends 120 only through a portion of their travel and at the same time roll and turn about their longitudinal axes. In consequence of the foregoing actions the ends of the needles are ground off evenly on all sides, thereby 125 effectively re-pointing a large number at a single operation.

The end of the bar 7 which in the form

illustrated has been shown prolonged beyond the boss 9 in a manner to engage the tone arm of the talking machine, it is obvious may engage any stationary part of the 5 talking machine or its casing, with the same result as the tone-arm 2. Or, instead of employing the balanced type of bar 7 in which the stop arm extension is oppositely disposed relatively to the disk supporting 10 end, a similar projection could be formed on the head of the screw 8 reaching radially sufficiently far to engage the tone arm or other stationary feature of the machine. The stop bar, in which ever form employed, 15 serves as means for not only rotatably mounting the member 6, but also for holding the part against rotatable movement when the device is in operation, in order to impart rotation to the disk 6 by the turn-table 3.

The utility of my invention will therefore be apparent. The construction is so simple that any person, however unskilled, can use the device to re-point a considerable 25 number of needles in a comparatively short space of time, and furthermore the operation of attaching and using the device does not injure or derange any portion of the talking machine, leaving the latter in condition to reproduce a record immediately 30 upon the bar 7 and disk 6 having been removed.

I do not wish to be restricted in the practice of my invention to the exact structural 35 details which I have illustrated and described; but I reserve the right to make changes in the shape, size, and arrangement of parts consistent with the nature of my invention, and embraced within the scope 40 and spirit of the latter, to the full extent in-

dicated by the general meanings of the terms in which the appended claims are expressed.

Having described my invention, what I believe to be new and desire to secure and protect by Letters Patent of the United 45 States is:—

1. A device for re-pointing phonographic needles, comprising a working member having a recess therein, and means for rotatably mounting said member in operative relation 50 to a talking machine.

2. A device for re-pointing phonographic needles, comprising a working member having a recess therein, and means for rotatably mounting said member in operative relation 55 to a talking machine and holding said member against translational movement when in operation.

3. A device for re-pointing phonographic needles, comprising a disk of abrasive material having a groove in one of its faces, and a bar whereon said disk is rotatably mounted, said groove being concentric with the axis of rotation of said disk, said disk carrying a closure for the groove, and the 60 bar having a boss extending laterally therefrom to engage the centering stud of a talking machine and support the disk with its periphery in contact with the turn-table of said machine, so that, when the turn-table 70 revolves, the disk will rotate, the bar being prolonged beyond the boss thereon to engage a relatively stationary part of the talking machine and prevent translational movement of the disk when the turn-table 75 rotates same.

Signed at New York in the county of New York and State of New York this 16th day of February A. D. 1918.

VICTOR H. EMERSON.
